UNITED STATES PATENT OFFICE.

EDGAR A. GILLINDER, OF PHILADELPHIA, PENNSYLVANIA, ASSIGNOR TO GILLINDER & SONS INC., OF PHILADELPHIA, PENNSYLVANIA, A CORPORATION OF PENNSYLVANIA.

CANTEEN GLASS GLOBE AND HOLDER FOR GASOLINE PUMPS.

Application filed May 8, 1926. Serial No. 107,701.

My invention relates to a new and useful improvement in canteen globes for gasoline service stations and the like, and it relates more particularly to a novel construction in 5 such canteen globes, whereby a more durable and less fragile globe is produced.

In constructing relatively large glass globes with relatively narrow neck portions, and particularly in constructing relatively 10 large flat glass globes, having a pair of relatively large flat opposed upright panels, such as canteen shaped glass globes for gasoline service stations, great difficulty has been experienced and disadvantage encountered 15 in the weakness of the usual neck or stem of the globe, secured in the usual socket having a series of set screws engaging a lower outwardly projecting flange on the neck of the globe, and particularly, the weakness of 20 such neck construction to resist the wind pressure upon the relatively large vertical faces or panels of such glass globe.

Thus, in the canteen glass globes for gasoline service stations, as constructed heretofore, with the usual outwardly extending bead or flange at the lower end of the neck thereof, adapted to be engaged by a series 25 of set screws throughout the periphery thereof in a usual socket, great loss has been incurred by the breakage of the globes in the neck portions thereof, due to the relatively great pressure of said set screws concentrated at a point of minute area, due also to the expansion of the glass when heated 30 and the rigid contact of such set screws, and due to the fact that the entire wind pressure upon the large and flat panels of such globes is borne by one or at the most two points in the periphery of the neck of the globe, that is, at the point or points of contact of the set screws. Particularly great 35 has been the loss due to the breakage of these globes in the mounting thereof, as the least amount of excess pressure of one of the 40 screws cracked the neck portion of the globe.

To overcome these disadvantages in canteen glass globes for gasoline service stations and to eliminate the great loss due 45 to the breakage of the same, various means have been devised. Thus, an attempt has been made to build canteen globes of this character of part metal and part glass, that is, to provide a cylindrical metal drum positioned upright and having a suitable me-

tallic neck portion, in which metallic cylindrical drum a pair of opposed relatively large circular glass discs or panels were inserted and secured by suitable means. This combination of metal and glass construction has been found to have inherent disadvantages in cutting down the net total illumination, or light emanating from such globe due to the opaque metallic surface forming a considerable portion of the globe. For this reason, these combined metal and glass globe 55 structures have been discarded and the all-glass canteen globes were resorted to in their stead, even at the considerable expense due to the breakage of these all-glass canteen globes, for the reasons hereinabove mentioned. 60

By my novel construction, I am enabled to provide all-glass globes for gasoline service stations, which will possess all the advantages of glass structures, that is, will give 65 a maximum of illumination from a given source of light within the globe, and will also be free of the objectionable feature of the glass globes of this character constructed heretofore, that is, will not be liable to breakage in the neck thereof, due to the pressure of the set screws bearing against the neck, and will have the durability of the combined 70 metal and glass globes of this character.

With the above ends in view, my invention 75 consists of an all-glass canteen globe for gasoline service stations, being of a generally circular form, having two opposed substantially parallel, and relatively large vertical panels formed integrally with the body of 80 the globe and having a lower pendant annular neck portion, having an outwardly projecting screw thread thereon formed integrally therewith.

My invention further consists of the combination of a canteen glass globe of this character with a novel threaded annular metallic protecting collar, preferably of sheet metal, adapted to be threaded onto the outside of the annular neck of said canteen 95 globe, so as to provide a glass neck surrounded by and encased within a corresponding, relatively light and resilient, metallic protecting collar. My invention further consists of a suitable lower pendant skirt or 100 rim upon said metallic protecting collar, adapted to be received in a suitable socket 105 and to be secured therein rigidly by a series

of set screws throughout the periphery thereof, or by any other suitable means.

For the purpose of illustrating my invention, I have shown in the accompanying drawings, forms thereof which are at present preferred by me since they will give in practice, satisfactory and reliable results, although it is to be understood that the various instrumentalities of which my invention consists can be variously arranged and organized and that my invention is not limited to the precise arrangement and organization of these instrumentalities as herein shown and described.

15 Referring to the drawings,

Figure 1 represents a perspective view of a novel canteen glass globe for gasoline service stations, and the novel metallic collar and mounting thereof, embodying my 20 invention.

Figure 2 represents a section on line 2—2 of Figure 1.

Figure 3 represents a perspective view of the metallic protecting collar.

25 Figure 4 represents a vertical section of the lower portion of the globe, on an enlarged scale, showing the detailed construction.

Figure 5 represents a section on line 5—5 30 of Figure 4.

Referring to the drawings, in which like reference characters indicate like parts, 1 designates the central annular and substantially cylindrical drum portion of the globe 2 35 having formed integral therewith the two parallel and opposed, relatively large circular and slightly convexed vertical panels 3 and 4, and having also formed integral therewith the lower pendant annular neck 40 portion 5, having suitable outwardly projecting thread 6, formed integral therewith. The glass globe 2 may be of any suitable glass, preferably of translucent milk glass, and the panels 3 and 4 being adapted to 45 have embossed, etched, painted or otherwise inscribed thereon, any inscriptions, indicia or the like.

The metallic annular protecting collar 7, 50 preferably formed of a slightly resilient sheet metal, comprising the upright annular threaded portion 8 of a pitch and diameter adapted to thread easily upon the outside of the lower thread 6 of the pendant neck 5 of the globe 2, and the outwardly and laterally projecting annular flange formed integral therewith, and the outwardly projecting vertical skirt or rim 10, also formed integral with the flange 9.

The protecting collar 7, is threaded onto the threaded neck portion until the upper 60 edge of said threaded member 8 of the protecting collar 7, substantially abuts the bead 11 on the neck 5 of the globe 2, immediately above the threads 6.

The globe is then positioned in the upper 65 holder 12 of the upper stem 13 of the usual gasoline pump and the set screws 14 are then screwed inwardly until they pass over the upper surface of the lateral flange 9 and bear against the lower portion of the annular threaded member 8.

Canteen globes thus supported in the holder or socket 12 on the top of the gasoline pump, are not only secure against 75 breakage due to wind pressure upon the large panels 3 and 4 thereof, but are also secure against any breakage due to undue tightening of the set screws 14, or due to any expansion of the glass neck 5 of the globe 2, since any strain of this nature is 80 taken up entirely by the metal protecting collar 7.

It will now be apparent that I have devised a new and useful construction in canteen glass globe for gasoline pumps, which 85 embodies the features of advantage enumerated as desirable in the statement of the invention and the above description, and while I have, in the present instance, shown and described a preferred embodiment thereof, which will give in practice satisfactory and reliable results, it is to be understood that such embodiment is susceptible of modification and variation in various particulars without departing from the spirit or scope 90 of the invention or sacrificing any of its advantages.

Having thus described my invention, what I claim as new and desire to secure by Letters Patent is:—

In a device of the character stated, a globe holder having a plurality of substantially radially disposed set screws extending inwardly, a threaded metallic protecting collar disposed within said holder, having a lower laterally projecting flange, a glass globe including a lower threaded glass neck portion threadedly seated in said metallic protecting collar, said lower lateral flange having a basal rim resting on the globe holder, and said radial set screws overhanging and operatively engaging said lateral flange firmly to clamp said protecting collar in said globe holder with the basal rim bearing against said globe holder.

EDGAR A. GILLINDER.
